FLEXIBLE MOP WITH FLEXIBLE BACK
CARRYING ABSORBENT MATERIAL
AND WITH HINGED COVER PLATEPeter S. Vosbikian and Thomas S. Vosbikian,
Mehrose, Pa.

Application June 13, 1949, Serial No. 98,658

3 Claims. (Cl. 15--119)

1

In our prior Patent No. 2,469,060, we have disclosed a novel, flexible mop head, wherein the sponge material is provided with a flexible back which also serves as a squeegee.

In our present construction of a flexible mop, we provide for assembling such basic construction with backing members hinged together in a novel manner and cooperating with a novel pressure transmitting member and a handle, with such component parts being retained in assembled condition by a single bolt. The pressure transmitting member retains the backing members in hinged relationship and places a tension on the backing members between their hinged connections and their outer ends.

A bracket carrying an auxiliary cleaning tool may also be employed as will be understood from the disclosure in our copending application Serial No. 97,032.

With the foregoing and other objects in view as will hereinafter clearly appear, our invention comprehends a novel flexible mop.

For the purpose of illustrating the invention, we have shown in the accompanying drawings a preferred embodiment of it which we have found in practice to give satisfactory and reliable results. It is, however, to be understood that the various instrumentalities of which the invention consists can be variously arranged and organized and the invention is not limited to the exact arrangement and organization of these instrumentalities as herein set forth.

Figure 1 is a perspective view of a flexible mop embodying our invention, the handle and nut being shown in detached position.

Figure 2 is a section taken on the same line of Figure 1 as Figure 4 showing the mop in wringing position.

Figure 3 is a perspective view showing the manner in which certain parts are assembled and having parts broken away.

Figure 4 is a section on line 4--4 of Figure 1.

Figure 5 is an end elevation with certain parts removed.

Similar numerals of reference indicate corresponding parts.

Referring to the drawings:

The basic construction is shown in Figure 5, which corresponds to our prior Patent No. 2,469,060.

Absorbent sponge material 1 is secured by adhesive to a flexible back 2, preferably of rubber, and a bolt 3 passes through the back centrally of the ends thereof and through the square, flattened end 4 of a handle 5 and is provided with a nut 6. Opposite marginal portions of the

2

back 2 have their under faces tapered as at 7, and overhanging the sponge material to form squeegees.

Combined cover and hinge plates 8 and 9, of identical construction, have opposite marginal portions deflected downwardly and inwardly to form grooves 10 and 11 to slidably receive the back 2. The inner marginal portion of each plate is rolled over as at 12 to receive the U-shaped hinge pins 13 and 14. Near the outer end of each plate the material is deflected to form a raised rib 15 to facilitate the grasping of the cover plates when extracting liquid from the sponge material. The back 2 may have raised ribs 16 to be received in the groove or recess formed by the deflected portion 15. This rib 16 may be omitted, if desired.

In order to retain the hinge pins 13 and 14 in their assembled condition with the cover plates and at the same time provide for their ready removal when it is desired to renew the unit formed by the sponge material and its back, we provide a pressure plate 17 having at opposite sides downwardly deflected ends to overhang the hinge pins and retain them in assembled condition with the plates 8 and 9, as shown at 18 and 19. Opposite marginal portions of the pressure plate are bent downwardly at an angle to bear against the cover plates intermediate their ends as will be understood from Figure 1 in which the cover plates are in longitudinal alignment. These bent portions are shown at 20 and 21. The pressure plate 17 has two parallel raised ribs 22 and 23 spaced to receive the square end of the handle at different angular positions of the handle relative to the pressure plate. The pressure plate is apertured at 24 to receive the bolt 3.

In assembling the cover plates 8 and 9, one plate is slid on one end portion of the back and the other plate is slid on the other end portion. The back 2 is sufficiently flexible to permit the raised ribs 16 to pass into the grooves formed by the deflected portions 15 of the cover plates. The hinge pins 13 and 14 are then inserted into the apertures formed by the rolled portions 12. The pressure plate is then applied, the bolt passing through the aperture 24 and the tabs formed by the end portions 18 and 19 overhang the hinge pins. The handle is located on the bolt and can be positioned in alignment with the longitudinal axis or the transverse axis of the mop, since the square end of the handle accurately fits the space between the ribs 22 and 23 which prevent angular displacement of the handle on the pressure plate.

When a new unit of sponge material and back

is to be assembled, the cover plates are removed as well as the pressure plate and the handle and a new unit can be assembled, as is apparent.

The liquid absorbed by the sponge material can be removed by pressing the cover plates downwardly and towards each other as will be understood from Figure 2, or the sponge material can be pressed against a conventional strainer. The raised ribs on the cover plates facilitate the grasping of the cover plates and prevents the slipping of the fingers thereon.

It will be apparent that the sponge material and back can be bent downwardly but their upward bending is restricted by the pressure plate. However, if it is desired to use the mop on irregular surfaces such as for example a basin or tub, or the floor and a base board, the handle can be applied directly to the unit of sponge material and back, or the unit can be grasped in the hand without using the handle.

While we have preferred to show two pintles inserted into knuckles, it is evident that one can be used with the two arms of greater length than those illustrated.

Having thus described our invention, what we claim as new and desire to secure by Letters Patent is:

1. In a mop, a block of absorbent material, a flexible back fixed to the top of the block, cover plates having grooves at opposite marginal portions to slidably receive said back, the inner ends of said cover plates being spaced from each other and deflected to form loops, pintles of U-shaped formation inserted into said loops, a pressure plate overhanging the inner ends of said cover plates and having downwardly deflected portions to limit pivotal movements in one direction of the back and block, and having downwardly deflected flanges to overhang the pintles and prevent their accidental removal, said cover plates having transversely extending grooves near their outer ends, said back having near its outer ends raised ribs to be received in said grooves and extending transversely of the

back, a handle, and a fastening device carried by the back midway of its ends and passing through the pressure plate and handle to secure the back and its block, the pressure plate and the handle in assembled condition.

5 2. In a mop, a block of sponge material, a back secured to the top face of the block, spaced cover plates connected with the back, the inner juxtaposed ends of the cover plates being hinged together in spaced relationship, a pressure plate extending across the space between the inner ends of the cover plates and having overhanging portions to contact each cover plate to limit their upward movement, the hinges having 10 pintles and the cover plates having end marginal portions deflected to contact the pintles to maintain the pintles in assembled condition, a handle having its lower end seated on top of the pressure plate, a bolt passing upwardly through the back, between the hinges, and through the pressure plate and the handle, and a nut for the bolt.

15 3. The construction defined in claim 2, wherein the back is longitudinally slidably in the cover plates and the back and cover plates have common thereto interlocking ribs and recesses.

PETER S. VOSBIKIAN.
